CLAIM

The ornamental design for a platform for stacking a pallet on top of a bulk bin or open ended box, as shown and described.

DESCRIPTION

FIG. 1 is a top perspective view of a platform for stacking a pallet on top of a bulk bin or open ended box;

FIG. 2 is a front elevation view of the platform for stacking a pallet on top of a bulk bin or open ended box;

FIG. 3 is a rear elevation view of the platform for stacking a pallet on top of a bulk bin or open ended box;

FIG. 4 is a right side elevation view of the platform for stacking a pallet on top of a bulk bin or open ended box;

FIG. 5 is a left side elevation view of the platform for stacking a pallet on top of a bulk bin or open ended box;

FIG. 6 is a top plan view of the platform for stacking a pallet on top of a bulk bin or open ended box;

FIG. 7 is a bottom plan view of the platform for stacking a pallet on top of a bulk bin or open ended box;

FIG. 8 is a bottom perspective view of the platform for stacking a pallet on top of a bulk bin or open ended box;

FIG. 9 is an alternate bottom plan view of the platform for stacking a pallet on top of a bulk bin or open ended box; and,

FIG. 10 is a bottom perspective view of the platform for stacking a pallet on top of a bulk bin or open ended box of FIG. 9.
